VARIABLE SPEED FRICTION DRIVE

Ralph Ragan, Atlanta, Ga.

Application June 5, 1930, Serial No. 459,396

7 Claims. (Cl. 74—199)

This invention relates to a variable speed friction drive.

One of the principal objects thereof is to provide a friction drive of the type wherein a drive wheel engages between the tapered faces of driven discs, in which the driving wheel will automatically position itself relative to the driven discs, in accordance with the load to be overcome, not only as the driving motor is started up but also as the speed of the driven discs increases, this automatic positioning of the driving wheel occurring throughout the variations of load.

Another object of the invention is to provide a drive of the friction type, in which the driving wheel is so disposed with relation to the driven discs that the former, upon the application of power, automatically digs in between the driven discs to pick up the load without slippage, and automatically applies the necessary power to the driven discs to take up the load.

Another object of the invention is to provide in a drive of the type mentioned, a construction in which the driving motor and the driving wheel are mounted as a unit upon an axis of oscillation so positioned with reference to the axis of rotation of the driven discs that the action of the driving wheel, and the weight of the motor are utilized in automatically positioning the driving wheel with reference to the driven discs to take up the load when the motor is started.

Another object of the invention is to provide a drive mechanism in which the driving wheel is so constructed as to equalize the application of power to the driven discs, and to eliminate friction and wear between the parts.

A further object of the invention is to provide a driving mechanism which may be readily applied to spinning frames now in operation at minimum expense, and with the occupation of minimum room and floor space, or to any other machine requiring this type of drive.

Another object is to provide means whereby the driven discs are adjustable to different distances apart, so that an adjustable speed friction drive is provided.

A further object of the invention is to provide means, where the drive is used in connection with a spinning frame of a cotton mill, to automatically increase the speed of the driven discs, and hence the spinning mechanism, as the layer thickness of the spun yarn on the bobbins increases, and in connection with this object of the invention, I have shown and described such means as an indexing mechanism particularly

suitable in connection with the method of winding the bobbins known as the warp build.

Another object is to provide in connection with the drive when applied to a spinning frame, indexing mechanism through the operation of which the driven discs are spaced further and further apart, in accordance with the layer thickness of the spun yarn on the bobbins, to automatically increase the speed of the spinning operation as the same proceeds, by allowing the driving wheel to enter further in between the driven discs.

A further object of the invention is to provide, in an indexing mechanism for automatically increasing the speed of the spinning machinery, means whereby the indexing mechanism may be quickly returned to position for beginning the spinning operation.

Another object is to provide in the indexing mechanism, means whereby the latter is actuated from the usual machinery incorporated in spinning frames.

Still another object of the invention is to provide novel frames for supporting the motor, and for supporting the bearing for the extension of the cylinder shaft of the spinning frame.

With these and other objects in view, which will become more apparent as the description proceeds, the invention resides in the construction, combination and arrangement of parts hereinafter more fully described, and claimed.

In the drawings which illustrate one of the forms the invention may take,—

Fig. 1 represents a side view, partially in section, of the drive, showing it applied to a spinning frame, the end of the latter being partially illustrated, and shown in section;

Fig. 2 represents a vertical sectional view through the driven discs, showing their assembly on the extension of the cylinder shaft;

Fig. 3 represents a sectional view on the line 3—3 of Fig. 2, showing the cam provided on the bushing on which the movable disc is mounted;

Fig. 4 represents a fragmentary elevational view of the movable driven discs from the opposite face of that shown in Fig. 3;

Fig. 5 represents an end view of the spinning frame, showing the drive mounted in respect thereto;

Fig. 6 represents an enlarged sectional view through the spring adjustment for the motor;

Fig. 7 represents a view, partially in section, showing the end frame of the spinning frame, looking from the inside of the spinning frame

towards the outside, in an opposite direction from that from which the showing of Fig. 5 is viewed;

Fig. 8 represents a transverse sectional view, partially in elevation, taken on the line 8—8 of Fig. 1, looking in the direction indicated by the arrows;

Fig. 9 represents a view, partially in section, taken at right angles to Fig. 8;

Fig. 10 represents a vertical sectional view 10 through the driving wheel which is mounted on the motor shaft;

Fig. 11 represents a view of the spider of the driving wheel;

Fig. 12 represents, on a reduced scale, a fragmentary inside elevational view of one of the discs of the driving wheel removed;

Fig. 13 represents an enlarged view, partially in section, of portions of the operating ratchet and trip lever of the indexing mechanism; and

Fig. 14 represents a view, partly in section, 20 showing a form of the drive where the discs are adjustable to different distances apart, to provide an adjustable speed drive.

Referring more particularly to the drawings, 25 the end frame of the spinning frame is indicated generally at A, the shaft of the "tin" cylinder of the spinning frame is indicated at B, the driven discs which are mounted on the extension C of such shaft are indicated at D and E, respectively, the bearing frame for the shaft extension is indicated generally at F, the driving wheel which is mounted on the motor shaft is indicated at G, the motor is indicated generally at H, and the motor supporting frame is indicated generally at I.

My drive is so constructed that there is no slippage between the driving wheel and the driven discs when the motor is started up, and, furthermore, the driving wheel automatically positions itself with reference to the driven discs in accordance with the load. As an aid to this end, the discs D and E are slightly flexible, and I have found that their flexing through a few, say in the neighborhood of twenty, thousandths 45 of an inch is sufficient. The working surfaces of the discs are tapered slightly, as at 4, such surfaces on the two discs opposing each other, and the operating surfaces of the driving wheel are tapered slightly, as at 5, to cooperate with the 50 tapered surfaces of the driven discs to transmit the power from the motor to the driven discs. The surfaces of the discs and wheel are preferably so formed that a line contact, of relatively short length, is formed between the driving wheel 55 and the discs. The motor and the driving wheel are mounted on an axis of oscillation so positioned with reference to the discs, and the driving wheel is rotated in such direction, that the driving wheel automatically digs in between the 60 discs and moves nearer to the axis of the latter as the motor is started up and as the discs come up to running speed, and, when the load is overcome and the discs come up to running speed 65 automatically moves outwardly or away from the axis to assume a position to transmit the required power for maintaining the speed of the load without unnecessary effort on the part of the motor, and without undue frictional resistance between the wheel and the discs.

70 In operation, the wheel, when the motor is started up, can be seen to move inwardly towards the vertical plane of the axis of the discs, and as the inertia of the load is overcome, to move outwardly as the speed increases, until it assumes 75 the proper position for maintaining the speed

of operation of the mechanism. If additional load is placed on the driven mechanism while it is rotating, to slow it down, the driving wheel will be seen to again dig in, until the added load has been overcome, and to move outwardly automatically to assume the correct position for maintaining the speed of the apparatus.

5 In order to obtain this automatic positioning of the driving wheel with respect to the load, in the particular installation illustrated, the axis 10 of oscillation which supports the driving wheel and motor is so positioned with reference to the spin axis of the discs that the line of contact between the driving wheel and discs, i. e., the line joining the axis O, of the wheel, and the spin 15 axis C of the discs, is maintained at some point within the octant of the discs which occurs on the side of the latter towards the driving wheel, immediately below the horizontal axis of the discs. Such octant is indicated in Fig. 5 at K. 20 Preferably, the contact is maintained throughout the inward and outward movement of the driving wheel within about 15°, comprising the central portion of such octant, as indicated at K', in Fig. 5. The radius of oscillation, i. e., the 25 line joining the axis O of the driving wheel, and the axis of oscillation 7, forms an oblique angle, and in the particular installation illustrated, an obtuse angle, with the line of contact between the driving wheel and discs, and the driving wheel 30 is rotated in such direction as to bring the successive lines of contact of the driving wheel into engagement with the driven discs, as such lines of contact are moving from within the obtuse angle toward the outside thereof, i. e., from below upwardly as viewed in Fig. 5 in the installation shown, or in a counter-clockwise direction. This arrangement and positioning of the driving wheel, and direction of rotation given it, thus causes the wheel to automatically tend to 35 ride "up hill" on the tapered surfaces of the discs, i. e., further in toward the axis of the discs, as the power is delivered to the latter, and hence to dig in between the discs. The latter will be driven in a clockwise direction. As the driving wheel oscillates in and out closer to and further from the axis of the driven discs, the line contact of the wheel follows an arc or curved line (indicated by the double dotted lines Z, Fig. 5) which, 40 extended, intersects the circumference of the driven 45 discs. In the arrangement shown the arc is located between the axis of oscillation and the axis of the discs.

55 It will be understood that the principles resulting in the digging-in action of the driving wheel and its automatic assumption of the correct position for maintaining the speed of the load, are not limited to the particular relative positioning of discs, wheel and axis of oscillation illustrated, but may be used in installations where other 60 relative positioning of these parts is used. That described is given for purposes of illustration.

Motor and supporting frame

65 I provide for the planetary movement of the driving wheel about its center of oscillation, without requiring a flexible connection between the driving wheel and motor, and take advantage of the weight of the motor to augment the effort 70 of the driving wheel in digging in between the driven discs to overcome the inertia of the load when the motor is started up. To this end, the motor base I, to which the motor is fixedly secured, is pivotally mounted on a bar or rod 6, the axis 75

7 whereof forms the axis of oscillation of the driving wheel and motor. The motor base 1 includes the body portion 7, thickened at its ends at 8^a, upon which ends the lugs or feet 9 of the 5 motor rest, cap screws or other suitable fastening means 10 passing through these parts to connect the motor to its base. Flanges 11 depend from the ends of the body portion of the base, being reinforced by the webs 12, and are provided with 10 bearings 13, which receive the bar 6. A rod 14 may connect the bearing portions of the flanges to rigidly maintain such portions in alignment. The motor base is also slideable longitudinally of the rod 6, not only to allow of the driving wheel 15 being correctly aligned with the driven discs, but also to allow of the bodily movement of the motor base, motor and driving wheel longitudinally of the rod as the driving wheel moves up the slope of one of the discs as the other separates under 20 action of the indexing mechanism, as will later appear.

The bar 6, at its inner end, toward the spinning frame, is carried in a bracket support, indicated generally at L, being locked therein by one or 25 more screws 15. The bracket support is provided with upper and lower sets of elongated slots 16, which receive bolts 17 which fix the bracket support upon the lower bar 18 of the machine frame A, such bolts at their inner ends passing through 30 a plate 19 on the inside of the bar 18, and receiving nuts for securely tightening the bolts in position. While the bar 6 and its bracket support L are of such strength that they will support the weight of the motor and the thrust imparted by 35 the drive when in operation, I may additionally support the outer end of the bar by means of the floor bracket M. Such bracket may be secured to the floor of the mill by suitable fastenings 20, and it is centrally slotted, as at 21, to receive 40 a cap screw 22, which engages into the end web 23 of the bar itself. The slots 16 in the bracket support L and in the floor bracket M are of such length as to allow the positioning of the motor supporting bar, and the support with which it is 45 associated, on spinning frames in which the lower end bars corresponding to 18 are at different distances from the mill floor.

The bearings 13, which pivotally support the motor upon the bar 6, are slightly offset, away 50 from the axis of the driven discs, with respect to the vertical plane of the axis O of the motor and driving wheel, when the latter are in the stationary position with the driving wheel engaging the discs. This positioning of the axis of 55 oscillation results in a tendency of the motor to tilt under its weight toward the discs, to thus augment the tendency of the driving wheel to dig in between such discs. I may also provide an additional weight, and, to this end, an arm 60 24 may extend outwardly from the motor base in the same direction in which the motor tilts as the driving wheel digs in, and carries a weight 25, which is adjustable along the arm toward and away from the motor, such weight being provided 65 with a set screw 26, which may be engaged with the arm to secure the weight in the adjusted position thereon.

In order to take up the increasing leverage of the motor in tending to increase the digging-in 70 action of the driving wheel as the motor tilts further towards the discs, and to limit the movement of the motor to prevent the line of contact from moving out of the effective octant of the discs, I provide a spring take-up, which may take the 75 form of reversed telescopic cups 26, within which

is mounted a coil compression spring 27, which tends to keep the cups separated, such take-up being mounted on an arm 28, clamped or otherwise suitably secured on the bar 6 and being positioned below the motor base on the side toward the discs, so that such base in tilting will tend to compress the spring. A roller 29 may be carried by the upper cup to engage with the under surface of the motor base, to provide a rolling contact between such base and the spring take-up 10 mechanism. The lower cup may be provided with a threaded stem 30, screwed into a threaded opening in the arm 28 and provided with nuts 31 to lock the lower cup in adjusted position with reference to the arm. The nuts may be loosened 15 and the cup screwed further up or lower down to the desired position to adjust the resistance of the spring to the tilting action of the motor to the desired degree. Adjustable stop means for arresting the movement of the motor at the desired angular position of the latter may take the form of a ring 32, threaded on the outside of the lower cup member and adjustable vertically thereon to limit the downward movement of the upper cup member, and hence the tilting movement of the motor. 20

The weight arm 24 may form a handle whereby the motor can be manually tilted backward away from the discs to disconnect the drive wheel therefrom, and whereby the motor can be shifted 30 bodily along the bar 6 to bring the drive wheel into proper alignment with the discs preparatory to engaging them before the motor is started up.

Shaft extension bearing frame

The discs D and E are mounted on the extension C of the cylinder shaft B, which projects outwardly beyond the end frame A of the spinning frame, and a bearing for the cylinder shaft may be provided in the cross-bar 33 of an H-frame N, which is bolted, as at 34, to the end frame A of the spinning frame. 40

The outer end of the shaft extension is supported in a bearing mounted within the housing 35, such housing being carried by a plate 36, 45 which is bolted or otherwise secured, as at 37, to the channel bar 38 of the bearing frame F. Such channel bar is horizontally arranged, and at its ends is bolted, as at 39, to inwardly extending extensions of the brackets 40, which latter are 50 bolted or otherwise secured, as at 41, to the uprights of the end frame A. The bearing for the shaft extension is thus rigidly supported on the end frame. It is made adjustable to frames of varying dimensions by reason of the slots receiving the bolts 37 and 41 being vertically extended (the slots for the bolts 41 being formed in the uprights of the end frame) and the slots for the bolts 39 being horizontally extended. The channel bar 38 is substantially U-shaped in vertical 55 section, the flanges of which fit over the extensions of the brackets 40, and such extensions are adjustable longitudinally with reference to the channel bar in order to adjust the bearing frame to the width of the particular spinning frame to 60 which it is to be attached. The brackets 40 may be cast with suitable webs 42, as illustrated, to make them strong and rigid in construction and at the same time light in weight. The bearing housing 35 may be provided with a cover 43, which is removable for purposes of inspecting 65 and grease-packing the bearings, such cover when in place forming with the housing a grease tight container for the bearing. 70

Disc assembly

The discs D and E are positioned on the shaft extension between the bearing of the latter and the end frame A. One of these discs, for instance 5 the disc D, is fixed with reference to the shaft of the cylinder, while the other disc, E, is movable longitudinally of such shaft (but not circumferentially thereof) toward and away from the disc D, under the control of the indexing mechanism, 10 later to be described. It may be here noted that, when the motor is started, the disc E is held by the indexing mechanism immovable with reference to the disc D, so that the digging-in movement of the driving wheel G is not due in any 15 respect to the bodily movement of the driven discs away from each other, but is permitted by the flexibility of the discs themselves. Under the control of the indexing mechanism, the disc E may move in a direction away from the disc D 20 during the running of the spinning frame, in order to allow the driving wheel to enter further between the discs, and hence increase the speed of the spinning frame as the layer thickness of the yarn on the bobbins increases, but this movement of the driving wheel further in between the discs, to increase the speed of the frame, as the discs are allowed to separate by the indexing mechanism, is not to be confused with the automatic inward or outward movement of the driving wheel with reference to the discs, in automatically adjusting the position of the driving wheel to take up the load that is required to be overcome. As the driving wheel enters further 30 between the discs under control of the indexing mechanism, it moves up on the taper of the disc D and at the same time is caused, by the camming action of the taper of the disc, to move longitudinally of the axis of oscillation, carrying with it the motor and motor base. 35

40 The driven disc D may be cast of suitable metal, such as iron, with radial webs 44 extending from the tapered flanges 45 of the disc to the hub 46 thereof, the tapered portion of the casting being machined, to make it as smooth and accurate as possible. The disc is secured in suitable fashion 45 as by machine screws 47, which may pass through enlargements formed in the webs 44, to the flange 48 formed on a sleeve 49, which is preferably made of stainless steel, or Monel metal, and which is fixed to the extension C of the cylinder shaft 50 of the spinning frame against movement with reference thereto.

Upon the sleeve 49 is mounted a bushing 50 made of suitable metal, such as bronze, and this 55 bushing is keyed, as at 51, onto the sleeve 49 for longitudinal sliding movement, but against rotative movement, with respect thereto. Upon the bronze bushing 50 the disc E is mounted, the hub of the disc being extended somewhat toward 60 the hub of the disc D, as at 52, and being reduced to receive a packing gland 53, to secure an oil packing 54 in position at the end of the hub, so that the bearing between the bronze bushing and the stainless steel sleeve will be 65 oiled. An oil duct 55 in the bushing communicates with an opening 56 in the hub of the disc E, to allow the packing to be oiled when desired. Except when oiling the packing, this duct is closed by a screw plug to retain the oil. The 70 packing and gland, in addition to retaining the oil for keeping the sleeve lubricated, prevents the oil from being sucked out of the sliding bearing under the influence of any partial vacuum that may be caused by the circulation of the air 75 through the air holes in the discs as the latter

revolve. These air holes are indicated at e, and are placed in the discs intermediate the webs 44 to allow the circulation of air, in order to keep the discs cool while running.

The disc E is similar to the disc D, except that its hub is extended to receive the packing gland and is provided with the oil opening, and is secured to the flange of the bushing by screws, similarly to the manner in which the disc D is fastened to the sleeve 49.

Where the drive is used in connection with the spinning frame, the position of the disc E with reference to the disc D is controlled by the indexing mechanism, later to be described. Suffice it to say, at this point, that this positioning occurs through the cooperation of cams on the indexing mechanism with a cam which is formed on the end of the bushing 50 toward the spinning frame, and which I refer to as the disc cam. This cam on the bushing includes the high flats 57, the low flats 58 which may be of substantially double the width of the high flats, and the slopes 59 which connect the high flat portions of the cams with the low flat portions thereof.

Driving wheel assembly

The driving wheel is mounted on the motor shaft, and is provided with a hub 60, tapered to fit the tapered end of the motor shaft, and is keyed against rotation with reference to the 30 shaft, as at 61, a washer and nut, as at 62 (see Fig. 1), being utilized to retain the wheel in place. From the hub 60 radiate spokes 63, connected by webs 64 at their ends towards the hub, such spokes being reduced at their outer ends at 65 35 to form bearings for receiving tapered spur gears 66. The latter are maintained in position by the rollers 67, which, being interposed between the driving disc 69, act as roller bearings, and even under the high pressure due to the wedging 40 action, tending to press the driving discs together, permit them to rotate freely in either direction with respect to each other. These rollers 67 are retained in place by the heads of the screws 68 carried at the ends of the spokes.

The driving discs 69 are mounted for rotation on the hub of the driving spider (which comprises such hub with its radiating spokes), the one of such discs nearest the motor being retained in place by a ring 70, carried on the hub 60, and the other of such driving discs being retained in place on the hub by the washer 62, already referred to. Such discs are of greater diameter than the driving spider, and at their outer edges are provided with inwardly extending flanges 71, one of which is reduced to provide a rib 72, which projects into a recess 73 formed in the opposing flange. The recess contains packing material to retain lubricant necessary for the moving parts contained within the driving wheel. The lubricant may be inserted through an opening 69a in one of the discs. A threaded plug ordinarily closes this opening.

The driving discs 69 are rotatable with reference to each other, and on their inner faces are 65 provided with tapered or beveled ring gears 74, which mesh with the tapered pinions 66. The driving wheel is thus in the form of a differential, to thereby equalize the transmission of power to the driven discs, and minimizes the frictional resistance between the driving wheel and the driven discs, and takes care of any mis-alignment that may occur between the driving wheel 70 and the driven discs.

The driving discs 69 on their outer faces, at 75

their peripheries, are recessed, as at 75, to receive annular composition rings 76, the outer edges of which rings are formed with the tapers 5, already referred to. Such composition rings are preferably made of highly compressed material impregnated with a lubricant, such as graphite, in order to minimize the frictional resistance between the driving wheel and the driven discs. While off-hand it would appear that frictional resistance between the two is desirable, I have found to the contrary that extremely good results are obtained when the coefficient of friction of the contacting surfaces of the driving wheel is very low. Good results may be obtained when the coefficient is between .50 and .10. I have also found that, by providing the differential in the driving wheel, the wear between such wheel and the driven discs is very materially reduced, and the heat generated during operation of the mechanism is kept at a low value. Tests have shown that the differential construction of the driving wheel, particularly when combined with the driving surface of low coefficient of friction, increases the efficiency of the drive, from the standpoint of power transmission, and minimization of wear and heat.

In installations where the alignment between the driving wheel and the driven discs can be maintained within close limits, I may use a solid driving wheel with composition rings or facings. Or I may use the differential driving wheel with the differential locked in suitable manner.

When the drive is used in an installation where adjustable speeds are desired, I provide means whereby the driven discs are adjustable to different distances apart, as shown in Fig. 14. In such figure, C' indicates the shaft to be driven, 49' indicates the sleeve mounted thereon and carrying the driven disc D'. E' indicates the other driven disc, movable toward and away from the disc B', the disc E' being mounted on the bushing 50', which may be keyed for longitudinal movement on the sleeve 49'. The end of the bushing beyond the disc E' from the disc D' may be reduced and threaded, as at 120, to receive the enlarged threaded end of an adjusting nut 121, against which the end of the bushing 50' abuts. A washer 122, carried on the end of the sleeve 49', forms a stop to limit the outward adjustment of the nut 121, and hence the opening of the disc E' with reference to the disc D'. The nut may carry a spring-pressed plunger or detent, having a rounded nose 123, which may engage with any one of a number of rounded sockets or depressions 124 formed in the end of the bushing 50' for locking the nut in adjusted position. The disc E' is maintained against the nut in any adjusted position of the latter, during the operation of the drive, by the wedging action of the driving wheel G' (there being illustrated a portion of a solid wheel with composition rings, as described). To decrease the speed, the driving wheel is disengaged and, when the shaft C' stops rotating, the nut is turned up to the desired amount to shift the disc E' toward the disc D', the engagement of the detent with the rounded sockets being such that the detent will be moved inwardly to allow the nut to turn, upon sufficient pressure being applied to the nut. If the speed is to be increased, the nut is rotated in the opposite direction, to the desired extent, to move outwardly away from the disc D', and the disc E' is shifted out to abut against the nut, the nut preferably being adjusted to a position where its detent will reengage with one of the sockets. After the adjustment the driving wheel, being again brought into driving

engagement with the discs, will drive the latter at a slower or greater rate of speed than before, depending upon whether the disc E' has been shifted toward or away from the disc D', the difference in speed, of course, being due to the fact that the engagement of the driving wheel with the discs will be at a point further from or closer to the axis of the discs, as the case may be.

Indexing mechanism

Where the drive is used in connection with a spinning frame of a cotton mill for instance, the indexing mechanism, now to be described, may be used in conjunction with the drive, to automatically increase the speed of the spinning frame as the layer thickness of the yarn on the bobbins increases, by allowing separation of the driven discs and consequent movement of the driving wheel closer and closer to the axis of rotation of the discs.

As is well known to those familiar with spinning frames, the ring rail of the frame carries the travellers which guide the yarn onto the bobbins and at the same time twists it. This ring rail is driven from the traverse cam lever of the frame through the intermediary of the builder motion. The traverse cam lever is moved by the builder cam, which in turn is driven by gearing from the "tin" cylinder shaft.

The indexing mechanism of my invention may be operated from the traverse cam lever, and I have illustrated a sufficient number of parts to indicate to those familiar with the operation of spinning frames how the indexing mechanism is actuated. In Fig. 5, the builder cam is indicated at 77, and the traverse cam lever at 78. The intermediate gearing between the cylinder shaft and the builder cam is not illustrated, as it is well understood. Nor is the ring rail and the associated mechanism, operated from the traverse cam lever, illustrated, as this also is understood. Suffice it to say that the lever 78 moves up and down under the influence of the builder cam as the cylinder shaft rotates. The indexing mechanism, which is mounted on the cylinder shaft, is operated from the traverse cam lever 78 by means of a flexible cable or cord 79, which runs over suitably disposed pulleys 80, and which connects with the upright arm 81 of a trip lever 82. Fig. 7 also shows these parts, such figure being viewed from the opposite direction from which Fig. 5 is viewed. The trip lever 82 may be pivoted at a convenient place, for instance, on a pin 83, carried by the H-frame N. A spiral torsional spring 84, engaging the pin and trip lever, normally retains the lever in raised position. A pin 85 may be used as a stop for the upward motion of the lever, a second pin 86 being used as a stop for the downward movement thereof. These pins may also be carried at convenient points, as by the frame N.

The cable 79 may terminate in the eye 87 of a bolt 88, which slides through an eye 89 formed at the upper end of the arm 81 of the trip lever. Beyond such eye a coil spring 90 surrounds the bolt, and adjusting nuts 91, mounted on the bolt, determine the distance that the bolt may move relatively to the arm before the compression of the spring imparts motion to the latter. It follows that the position of the nuts on the bolt determines the distance that the traverse cam lever 78 may move downwardly before shifting the trip lever 82 downwardly. If the nuts 91 are adjusted close to the arm 81, the arm will move downwardly at the beginning of the downward movement of the traverse cam lever. If, on the

other hand, the nuts are adjusted away from the arm 81 the cam lever will move downwardly through a portion of its throw, before the compression of the spring picks up and moves the lever 82 downwardly. It will thus be understood that the time, during a cycle of movement of the traverse cam lever down and up, that the trip lever is depressed, is under control of the operator through adjustment of the nuts 91.

As will later appear, a ratchet arm, through which the indexing mechanism is driven, rotates with the cylinder shaft and is tripped by contacting with the trip lever 82, to move the indexing mechanism. Such indexing mechanism is moved a greater or less distance during each cycle of movement of the traverse cam lever, depending upon whether the trip lever 82 is depressed early or late respectively with reference to such cycle of movement. The sooner the trip lever is depressed by operation of the traverse cam lever, the further the indexing mechanism is moved, and the greater the rate of increase of speed of the spinning frame under the control of the indexing mechanism. This because the cylinder shaft rotates many times during a cycle of movement of the traverse cam lever, and upon each of its revolutions the ratchet arm will be actuated by the trip lever to move the indexing mechanism one space. The later the depression of the lever 82, the fewer the times the ratchet arm will be tripped during the cycle of movement of the traverse cam lever, and the less the rate of increase of speed of the spinning frame.

The indexing mechanism includes a ring-shaped casting P, which is made in halves, secured together about the sleeve 49, carried on the cylinder shaft. Such ring or casting fits into a channel 92, formed circumferentially of the sleeve (see Fig. 2), the halves of the ring or casting being secured together by the machine screws 93. The casting rotates with the sleeve 49, and consequently with the cylinder shaft. Rotatably mounted on the sleeve 49, between the ring P and the adjacent cam-shaped end of the bushing 50, i. e., the disc cam, is a gear wheel R, and this gear, on the side toward the bushing 50, is provided with cams 94, which cooperate with the cams formed on the bushing.

As illustrated, for instance in Fig. 9, the cams 94, i. e., the cams of the indexing mechanism, are opposite the high flats of the disc cam. The disc E, therefore, is relatively close to the disc D. As the gear R slowly rotates through the operation of the indexing mechanism, the cams 94 move off of the high flats of the disc cam, and gradually move down the slopes of the latter. This allows the disc E to move longitudinally of the sleeve 49 outwardly away from the disc D, thus increasing the space between these discs, and allowing the driving wheel to enter further between the discs, and hence increase the speed of the cylinder shaft, and consequently of the spinning frame. The ring or casting P, in conjunction with the shouldered portion of the sleeve 49, formed by reason of the channel 92 in which the ring is clamped, takes up the thrust of the disc E longitudinally of the cylinder shaft.

The gear R is driven by a worm S, disposed between the ears 95 and 96, which are formed on one edge of the ring or casting P, one on each of the halves of such casting. The shaft 97 of the worm S has a bearing in such ears.

Carried on the worm shaft 97, beyond the ear 96, and slidably longitudinally of such shaft, but held against rotation relatively thereto, is an in-

dex gear T. This gear is much smaller relatively than the gear R, and in turn is driven by a smaller worm U, the shaft of which is journaled in an ear 98, formed on the casting or ring P. On the extension of the shaft 99 of worm U, beyond the ear 98, is keyed a toothed ratchet gear W, a portion of such gear, reduced in diameter as at 100, separating the toothed portion of the gear from the face of the ring P and the ear 98. A collar 101 surrounds the ratchet gear W (see Figs. 9 and 13), such collar having a reduced portion 102, which bears on the reduced portion or shoulder 100 of the ratchet gear W, and having an opening of a size to receive the ratchet gear, the portion 103 surrounding such opening bearing upon a washer 104, which is mounted on the shaft 99 of worm U, beyond the ratchet W. A plate 105, of diameter greater than that of the washer 104, is fixed on the end of the shaft by a screw 106, or other means, thus retaining the collar and ratchet gear in assembled position on the shaft. The collar is free to rotate, relatively to the ratchet gear, upon the bearings formed by the shoulder 100 and the washer 104. This collar has formed therewith the ratchet arm X, bearing a roller 107 at its outer end. A ratchet pin 108, spring pressed as at 109, mounted in the ratchet arm X, engages the teeth of the ratchet wheel W.

The ratchet arm cooperates with the trip lever 82, in actuating the indexing mechanism. The direction of rotation of the cylinder shaft, and the indexing mechanism as a whole, is indicated by the arrow in Figs. 7 and 13. The lever 82 is curved, the curvature being such as to approximate the orbit of the roller 107 at the outer end of ratchet arm X, so that, when the trip lever is in fully raised position, the ratchet arm X will rotate bodily about the center of rotation of the cylinder shaft, without the roller 107 engaging with such trip lever. When the trip lever is depressed, however, it will intersect the orbit of the roller 107 sufficiently to throw the ratchet arm backward a distance such that the pin 108 will move the distance of one tooth of the ratchet W. Upon the ratchet arm moving from beneath the trip lever, centrifugal force will throw the ratchet arm back to its original position, thus moving the ratchet W one tooth, and, as a consequence, through the medium of the worm U, index gear T and worm S rotating the gear R, and hence shifting the index cams 94 with respect to the disc cam a distance which will correspond to the shift of the ratchet through one tooth.

By reason of the adjustability of the time of depression of the trip lever with respect to the cycle of movement of the traverse cam lever as before explained, the indexing mechanism can be adjusted so as not to be actuated at all as the cylinder shaft rotates, and hence the cylinder shaft speed be kept constant throughout the period of winding of the yarn upon the bobbins, or the adjustment can be such that the indexing mechanism can be actuated and to a small or greater number of times during the spinning operation, so that the rate of increase of speed of the spinning mechanism is under control and may be adjusted as desired.

In winding the bobbins in the manner known as the "warp build", it is desirable to maintain the speed of the cylinder shaft constant, until the layer thickness of the yarn on the bobbins reaches a certain point, at which time it is then desirable to start the increase of speed of the cylinder shaft. In my mechanism, the indexing cams, at the beginning of the operation of wind-

ing the bobbins, are set, in the manner later to be explained, on the high flats 57 of the disc cam. The time of throw of the trip lever will have been adjusted as desired. As the machine 5 starts up and the traverse cam lever moves up and down, the operating ratchet, upon each rotation of the cylinder shaft after the trip lever is depressed, will be kicked back by the lever, and again thrown forwardly by centrifugal action, to 10 actuate the indexing mechanism. The speed, however, of the cylinder shaft will remain constant, because the indexing cams are moving over the high flats of the disc cam. This relative movement of the cams will continue to the point 15 where the desired thickness of the wound yarn on the bobbins will have been reached, whereupon the indexing cams will have reached the ends of the high flats of the disc cam and will start down the slopes of the latter. The continued actuation of the indexing mechanism will 20 thus move the indexing cams further around, thus allowing, through the bevel of the slopes, the disc E to move outwardly with reference to the disc D, and hence the driving wheel to move 25 further in between the discs, thus increasing the speed of the spinning frame as the layer thickness of the wound yarn increases. When the indexing cams have reached the low flats of the disc cam, the speed will again become constant, 30 but will be high with reference to the beginning of the operation, and this latter constant speed will be maintained until the bobbins are full and it is time to doff.

The forward throw of the operating ratchet 35 arm X is limited, and this may be accomplished by a pin 110, carried by the casting P, fitting into a groove 111, formed in the inner edge of the collar 101, which carries the ratchet arm. By reason of the shoulder at the end of such groove 40 engaging the pin as the ratchet is thrown forwardly, such forward movement is stopped and the ratchet held in a predetermined forward position. It will maintain this position, under the influence of centrifugal force, except when it 45 is thrown rearwardly by engagement with the trip lever.

Concerning now the method of returning the indexing cam to original position at the beginning of the spinning operation, it will be observed 50 that the index gear T is movable longitudinally of the shaft 97 of worm S, being held against rotation by a spring-pressed key 112, the shank 113 of which fits into an opening in the shaft 97, above a spring 114. This key is shouldered, as at 115 55 (see Fig. 8), and the shoulder retains the index gear T in engagement with the worm U during normal operation of the indexing mechanism. When, however, the doffing period has been reached and the machine stopped, the key 112 60 is depressed by the operator and the index gear T pulled outwardly, which will disengage it from the worm U, whereupon the gear may be rotated by hand to quickly rotate the gear R, and hence the index cams, until they have assumed their 65 correct position on the high flats of the disc cam for the beginning of the spinning operation. A washer 116, secured on the outer end of the worm shaft 97 by a screw 117, prevents the gear T from being accidentally withdrawn from the shaft, but 70 allows the gear to be entirely disengaged from the worm U, so as to clear the latter as the indexing mechanism is reset. It will be understood that the motor, at the end of the spinning operation, will have been thrown by hand to the 75 left, to tilt the driving wheel out of engagement

with the driven discs, so that the rotation of the indexing gear to initial position will shift the driven disc E to its initial relatively close position with respect to disc D. The disc E may be moved over to initial position by hand first, and the indexing mechanism then reset, if desired. 5

In order to counterbalance the weight of the driving mechanism for the gear R, which is assembled substantially on one side of the axis of the collar P, the latter, on the opposite side of such axis, is weighted, as at 118. The entire indexing mechanism is thus balanced with reference to the axis of rotation of the cylinder shaft. 10

The shape of the disc cam and the indexing cams illustrated has been found to be of use in 15 connection with the formation of a "warp build", but it will be understood that the shapes and the proportions of the cams may be modified to secure the desired ends with reference to the time of desired dwells and intervals occurring there- 20 between.

It will be understood that, if desired, the trip lever for operating the indexing mechanism may be disconnected from the traverse cam lever, in 25 which case the indexing mechanism will not operate during the spinning operation and the speed of the cylinder will remain constant. Such speed may, however, be increased or decreased by manually adjusting the indexing mechanism to maintain the disc E further from or closer 30 to the disc D to the extent desired.

From the foregoing, the construction and operation of the invention are believed to be clear without further description.

The detailed description and illustration of 35 the invention have been given for purposes of clearness of understanding, and no undue limitations should be deduced therefrom, but the appended claims should be construed as broadly as permissible, in view of the prior art. 40

Having thus described my invention, what I claim as new and desire to secure by Letters Patent is:—

1. In a variable speed friction drive, a driving 45 wheel comprising a hub adapted to be mounted on the shaft of a motor, relatively rotatable driving discs journaled on the hub and each having a tapered working surface, interengaging differential gearing between the driving discs and hub, and interengaging lubricant retaining means between the discs beyond the differential gearing from the hub. 50

2. In a variable speed friction drive, the combination of a driving wheel having tapered working surfaces, a pair of driven discs having tapered working surfaces adapted to be engaged by the working surfaces of the driving wheel, a sleeve upon which one of the driven discs is fixed and upon which the other disc is keyed for longitudinal movement toward and away from the said one disc, lubricating means between the said other disc and sleeve, and means for retaining the lubricating means in place. 55

3. In a variable speed friction drive, driven discs for transmitting power to a shaft to be 65 rotated, comprising a flanged sleeve adapted to be mounted on the shaft, a disc fixed on the flange of said sleeve, a flanged bushing mounted on the sleeve for longitudinal and against rotary movement relatively thereto, another disc fixed to the 70 flange of the bushing, and lubricating means between the sleeve and bushing.

4. In a variable speed friction drive for spinning frames, the combination of driven discs mounted on the cylinder shaft of the spinning 75

frame, one of said discs being movable toward and away from the other and being provided with a cam, a driving wheel adapted to engage the driven discs and to move toward the shaft as the discs separate for increasing the speed of the discs and shaft, and indexing mechanism rotatably mounted on the shaft and having a cam cooperating with the cam of the movable disc whereby the movable disc can be moved longitudinally of the shaft as the indexing mechanism is actuated, and means operable from the spinning frame for actuating the indexing mechanism.

5. In a variable speed friction drive for spinning frames, the combination of driven discs for 15 rotating the cylinder shaft of the frame, including an axially movable disc provided with a cam, and indexing mechanism having a cam cooperating with the disc cam whereby the disc can be moved axially as the indexing mechanism is actuated, means operable by mechanism of the 20 spinning frame for actuating the indexing mechanism and driving means for the driven discs adapted to move said movable disc axially under permission of said indexing mechanism and to 25 simultaneously move inwardly nearer the center of the discs.

6. In a variable speed friction drive for spinning frames, the combination of a driven disc for operating the shaft of the frame and movable longitudinally of the shaft, and indexing mechanism mounted on the shaft, including a cam adapting the disc for adjustment longitudinally of the shaft and including a ratchet mechanism and intermediate gearing between the ratchet mechanism and cam for actuating the latter as the ratchet mechanism is actuated, and means operable by the spinning frame adapted to actuate the ratchet mechanism.

7. In a variable speed friction drive for spinning frames, the combination of a driven disc 15 mounted on the cylinder shaft of the frame for rotating the shaft and being movable longitudinally of such shaft, indexing mechanism including a cam adapted to cooperate with the driven disc for determining the position of the latter 20 longitudinally of the shaft, and a train of gearing for operating said cam including a gear detachable from the train and adapted to be manually actuated for returning the cam to initial position.

25 RALPH RAGAN.
